UNITED STATES PATENT OFFICE.

JOHN E. CARROLL AND WILLIAM H. ANDREWS, OF BOSTON, MASSACHUSETTS,
ASSIGNORS, BY MESNE ASSIGNMENTS, TO WIZARD TIRE INFLATOR & FIRE
EXTINGUISHER CO., A CORPORATION OF MASSACHUSETTS.

DISCHARGE CONTROL FOR FLUID-RECEPTACLES.

1,152,485.

Specification of Letters Patent.

Patented Sept. 7, 1915.

Application filed January 10, 1914. Serial No. 811,459.

To all whom it may concern:

Be it known that we, JOHN E. CARROLL and WILLIAM H. ANDREWS, both citizens of the United States, and residents of Boston, 5 in the county of Suffolk and State of Massachusetts, have invented new and useful Improvements in Discharge Control for Fluid-Receptacles, of which the following is a specification.

10 Our invention relates to discharge control of receptacles for fluid under pressure, particularly for receptacles containing in liquid form fluid which at the prevailing temperature and at normal pressure is gaseous; such as, for instance, liquid air or liquid carbonic 15 dioxid. For lack of a better definitive general term, we will refer to fluids of the character indicated as "liquid gas."

In particular, our invention is intended 20 for use with fluid receptacles to be used for inflating pneumatic tires, and comprises devices which, while especially adapted to this service, may well be used in other situations.

The apparatus we have invented belongs 25 to that class in which the act of inserting a tubular nipple causes the intruded nipple to lift a check valve and permit the escape of fluid confined in the receptacle through the tubular nipple to whatever place the dis- 30 charged fluid is destined. No apparatus of this class, however, so far as we are aware, has presented a construction which adapts its working parts to effective or prolonged service in receptacles containing fluids un- 35 der very high pressure. To the latter condition our invention is particularly ad- dressed.

In the drawings hereto annexed in which we illustrate our invention, Figure 1 shows, 40 in cross section, a tire-inflating "bottle" which comprises our invention; and Fig. 2 shows, in cross section, much enlarged, the receptacle closure and valve control which characterize our invention.

45 The bottle F, composed by preference of seamless sheet steel, drawn to tubular shape, is originally in two parts, each of more or less elongated cup-shape; these are joined by electro-welding or other welding process 50 at the line F'. Before the completion of the

closed bottle by welding, the closure and discharge control devices are assembled in the end of one of the steel cup-shaped members. These devices are best shown in Fig. 2.

The closure comprises, an apertured plug 55 B, B', externally and internally threaded, and a cap D, D'. These two members are screwed together, B, B' outside and D, D' inside, the cup-shaped member F. A packing ring C is clamped between the flange of 60 the plug B, B', and the wall of the receptacle F. Within the hollow top of the cap D, D' the valve E is housed. This valve is preferably composed of flexible material, such as rubber, and is provided with two recesses E' in its lower, or seating side. The flexible valve E seats on the inner end of the plug B, B', which is furnished with an annular ridge B². The members B, B', and 65 D, D', are both, by preference, composed of 70 a readily fusible metal, such for instance, as that employed in automatic fire-sprinklers, so that, in case the fluid receptacle should be exposed to great heat, there will be less danger of its exploding, since the fusion of the 75 closure members, or either of them, will permit the retained fluid to escape from the receptacle. The valve E is so placed that when the receptacle F is screwed on to the tubular nipple A, the end of the nipple will 80 finally intrude into the receptacle far enough to lift the valve E from its seat. In the specific instance used for illustration, the nipple A is the threaded valve containing 85 stem of a pneumatic tire, and, as these stems in the standard form are provided each with a conical shoulder A', we employ this shoulder, and a coacting conical surface A⁵ in the central perforation of the closure 90 plug B, B', to limit the intrusion of the nipple A into the receptacle F, so that the maximum opening of the valve E is predetermined.

Since the receptacle F is intended to carry fluid, or "liquid gas", under very great 95 pressure—as high as 3000 pounds to the square inch,—it is obvious that it would not be practicable to attempt lifting a valve of any considerable area. Furthermore, if a very small valve were employed, with a cor- 100

respondingly small area to bear upon a valve-lifter,—such as the tubular nipple A, the effective pressure per square inch upon the coating surfaces would be too high for practical service. In order to reconcile these two desiderata—small valve opening and large bearing surface for the valve-lifter,—we have contrived the flexible valve illustrated in the drawings, and means for opening this valve one-sidedly.

The valve E is opened by the end of the valve-lifter A, when the latter rises above the valve seat. If the plane of the valve seat, and that of the end of the valve-lifter, are always parallel, the tendency will be to lift the valve squarely from its seat, and this would require high pressure between the valve and the lifter, pressure so high that even were both valve and lifter of equally resistant material, one or both would eventually become injured. In order to avoid this, we shape the plane of the valve seat and that of the end of the valve-lifter so that they stand at a slight angle to one another. In the specific instance shown in the drawings this is accomplished by giving the valve seating surface of B, B', a slight angle or bevel, so that the side B⁴ is lower than the side B³. With a valve seat about five-eighths of an inch in extreme diameter, a slope of one-thirty-second of an inch will suffice. Thus, the upper end of the valve-lifter A first strikes the valve E at the point A⁴, and, as the valve is flexible, the lifter soon secures ample bearing on the valve, and yet has to overcome only a small total pressure, since the edge only of the valve E has to be lifted. It is as though a thin knife blade were insinuated under one edge of the valve. Communication between the receptacle F and the interior of the cap D' is maintained, as through an aperture D².

The annular ridge B² serves not only to insure tight seating of the valve E, but, when this valve is lifted one-sidedly, holds the high side of the valve in position, as though by a hinge, and makes certain the accurate return of the valve E to its original seat. The valve E is put in place with the spring G (which may be dispensed with) pressing it lightly to its seat; thus final and secure seating is effected when the fluid contents of the receptacle F are injected under pressure. The recess in the valve E is preferably in two places, E', E', so that, however the valve E may place itself on the seat, one or both of the recesses E' will provide a passage for fluid escaping into the tubular valve lifter A.

When, as we intend, the above described receptacle and discharging devices are used to hold and to discharge "liquid gas," like liquid carbonic dioxid, the following rule of construction should be followed. In a se-

ries of experiments we met with difficulty due to the production of intense cold at constricted areas in the discharge conduit, and consequent accumulation of frost, which effectively put the apparatus out of action. This takes place whenever a constriction leads to an expanded area, so that expansion and production of gas from liquid takes place abruptly, absorbing heat and frosting the surface. We so arrange the predetermined maximum opening of the valve E with respect to the passages in the conduit leading forth from the receptacle F, that at no point in the conduit itself will the cross sectional area be materially greater than it is at the valve opening. Then, if the receptacle be applied to the valve lifter mouth down, all the contents will flow as liquid, through the conduit, not expanding into gas until the discharge end is reached, where the accumulation of frost will do no harm, if it occurs. In the instance herein shown, the inner end of the tire valve stem A is the place where "liquid gas" changes from liquid to gaseous form; the object of using our fluid-receptacle in this case is to charge the tire tube with gas under pressure.

What we claim and desire to secure by Letters Patent is:

1. In a closure for receptacles for fluid under pressure, the combination of an apertured member provided with a valve seat, a flexible valve coöperating with said valve seat, and a valve lifter movable to engage the flexible valve and unseat it by deformation of the valve.
2. In a closure for receptacles for fluid under pressure, the combination of an apertured member provided with a valve seat, a flexible valve coöperating with said valve seat, and a valve lifter movable to engage the flexible valve at one side thereof and unseat it by deformation of the valve.
3. In a closure for receptacles for fluid under pressure, the combination of an apertured member provided with a valve seat, a flexible valve coöperating with said valve seat, and a valve lifter movable to engage the flexible valve and unseat it by deformation of the valve, and means to limit the valve-deforming movement of the valve lifter.
4. In a closure for receptacles for fluid under pressure, the combination of an apertured member provided with a valve seat, a flexible valve coöperating with said seat and having a recess on its seating side, and a tubular valve lifter movable to engage the flexible valve and unseat it by deformation of the valve, said recess in the valve providing a way for escaping fluid into the valve lifter.
5. In a closure for receptacles for fluid under pressure, the combination of an aper-

tured member provided with a valve seat, a flexible valve coöperating with said seat, and a valve lifter movable in said apertured member to engage the valve and unseat it
5 by deformation of the valve, the valve-engaging surfaces of the valve seat and valve lifter lying in planes at an angle to each other.

Signed by us at Boston, Massachusetts,
this twenty-ninth day of December, 1913. 10

JOHN E. CARROLL.
WILLIAM H. ANDREWS.
